OSCAR M. BROOKS AND ROBERT W. SOPER, OF JANESVILLE, WISCONSIN

Letters Patent No. 66,457, dated July 9, 1867.

IMPROVED BURGLAR-ALARM.

The Schedule referred to in these Letters Patent and making part of the same.

TO ALL WHOM IT MAY CONCERN:

Be it known that we, OSCAR M. BROOKS and ROBERT W. SOPER, of the city of Janesville, in the county of Rock, and State of Wisconsin, have invented a new and improved Burglar-Alarm; and we do hereby declare that the following is a full and exact description thereof, reference being had to the accompanying drawings, in which—

Figure 1 is a side view of my burglar-alarm with the hammer down.

Figure 2 is a side view, with the hammer "cocked" of the same, as used without the barrel for igniting powder.

Figure 3 is a front or end view of the same as it appears in fig. 1, but with the barrel (C) detached.

Figure 4 is a top view of the same as it appears in fig. 1, but with the hammer cocked.

Figure 5 is the same as fig. 2, but with the side plate or cap A removed so as to show interior construction and arrangement.

Figure 6 is a cross-section through the cap and nipple.

Figure 7 is a top view of my burglar-alarm as it appears in fig. 2, with section of door and lock, showing the manner of its attachment to the latter; and

Figures 8 and 9 show how the match-holder is attached to the body of the alarm.

The nature of my invention consists, first, in attaching a burglar-alarm to a door-lock by means of a screw-button, substantially as hereinafter described; second, in constructing a burglar-alarm so that the movement by the burglar of a tripping-lever of the alarm that is inserted in the key-hole shall cause a match to be lighted and a cap or charge of powder in an attached barrel to be fired, substantially as hereinafter described; third, in supporting the match in an adjustable holder and lighting it directly by the fire of the cap or of the ignited powder in the barrel, should the latter be used, substantially as hereinafter described.

To enable others skilled in the art to make and use my invention, I will proceed to describe its construction and operation.

It consists of a suitable case, A', having ordinarily an open side covered by a plate or cap, A, and provided with the ordinary appendages of a gun-lock, as a hammer, B, main-spring l, nipple s, for the cap b, dog H, and dog-spring n. This dog H has its upper end H' turned up and bevelled as shown. The bevelled or inclined faces meeting in an obtuse angle play in a groove in the tripping-lever G that has its faces similarly inclined, as shown in fig. 4. The connection of the dog and tripping-lever, it will be seen, is such that if the latter be pulled out, or shoved in, or turned, the upper end H' of the dog is driven forward, thus setting free the hammer B to fall upon the cap b. The end of the tripping-lever that is inserted in the key-hole has a pin, h, fig. 3 projecting, as shown, to cause the tripping-lever to be moved, and consequently the alarm to be given at the slightest attempt to pick the lock. The lower part of the nipple s is expanded into or connected to a short barrel C', that has an orifice, u, connecting with that in the crown of the nipple, as shown in fig. 6. The part C' is fitted to receive the barrel C, as shown. The latter is provided with a vent, k, for allowing sufficient fire to escape to light the match E. The match is supported in a holder, D F, attached to the bottom plate of the case A', as shown in figs. 5, 8, and 9, so as to allow the match to be turned freely either to a position facing the vent k in the barrel when the latter is used, as shown in figs. 1 and 4, or facing the orifice u in the part C' when the barrel is not used, as shown in figs. 2, 3, 5, and 6. To hold my device in the key-hole of the door or lock I provide it with a part, d, that screws in and through the case A' and terminates, as to its inner end, in a head, i, having two lateral spurs projecting from its opposite sides after the manner of the ordinary door-button. These spurs, when the part is screwed out to the proper distance, is designed to catch within the lips a' of the key-hole L or of the lock K, as shown in fig. 7, and so hold the whole device in the desired position. In fig. 7 K represents the lock and I a section of the door.

To operate my device it is only necessary to place the match E in the holder F, and then turn it to the position shown in figs. 1 and 4, or that shown in figs. 2, 3, 5, and 6, as the barrel C may or may not be used. Then, having cocked the hammer B, placed a cap, b, upon the nipple s, and inserted the tripping-lever G in the key-hole of the door to be guarded, and having secured the device in that position by turning the screw-button d i, as shown in fig. 7, we may placidly await the attempt to pick the lock that shall move the tripping-lever G, and thus releasing the hammer cause the latter to fire the cap or the charge in the barrel and ignite the match, so as to alarm the burglar and arouse the occupants of the room, and at the same time afford the latter a temporary light.

What we claim as new, and for which we desire Letters Patent of the United States, is—

1. The construction and arrangement of a burglar-alarm in such a manner that the movement by the burglar of the tripping-lever G, that is inserted in the key-hole of the door to be guarded, shall cause a match to be lighted and a cap or a charge of powder in an attached barrel to be fired, substantially as and for the purpose described.
2. The combination and arrangement of the tripping-lever G with the dog H and hammer B, substantially as and for the purpose set forth.
3. The match-holder D F, when constructed as described and used to adjust a match either in front of the vent k or the orifice u, substantially as and for the purpose described.
4. The combination and arrangement of the hammer B, nipple S, and part C', with the match-holder D F in such a manner that the hammer does not strike the match but fires it by the explosion of the cap, substantially as and for the purpose described.
5. The combination and arrangement of the hammer B, nipple s, part C', barrel C, and match-holder D F, substantially as and for the purpose set forth.
6. Securing a burglar-alarm in the key-hole of a door by means of the screw-button d i, substantially as and for the purpose set forth.

OSCAR M. BROOKS,
ROBERT W. SOPER.
